UNITED STATES PATENT OFFICE.

MAX BREMER, OF NEW BEDFORD, MASSACHUSETTS, ASSIGNOR TO THE PAIRPOINT MANUFACTURING COMPANY, OF SAME PLACE.

DESIGN FOR A CASKET-HANDLE EAR.

SPECIFICATION forming part of Design No. 20,714, dated May 12, 1891.

Application filed February 11, 1891. Serial No. 381,087. Term of patent 14 years.

To all whom it may concern:

Be it known that I, MAX BREMER, of New Bedford, in the county of Bristol and State of Massachusetts, have invented and produced 5 a new and original Design for a Casket-Handle Ear, of which the following is a specification, reference being had to the accompanying drawings, forming part thereof.

Figure 1 is a plan of an ear, showing my 10 design. Fig. 2 is a sectional view on line 2 2 of Fig. 1.

My design consists in two parallel swells with a depression between them, one of the swells being at a margin of the ear and one 15 wall of the other swell being extended downwardly and outwardly to that margin of the ear which is opposite the marginal swell.

A is the marginal swell; A', the second parallel swell; a, the depression between them.

The wall a' of swell A' is extended outwardly 20 to the margin A². The edges $b b$, adjacent to the marginal swell A, are usually inclined (and this is a feature of my design) from the base of the ear upwardly and inwardly, and the edge b' is usually curved, as shown. The 25 ear is formed with any suitable arm-socket B.

What I claim is—

The design for a casket-handle ear herein shown and described, the same comprising the marginal swell A, the parallel swell A', 30 the depression a between swells A A', the curved extension a' , and inclined edges $b b$, as set forth.

MAX BREMER.
